UNITED STATES PATENT OFFICE.

NICHOLAS BURKART, OF LOS ANGELES, CALIFORNIA.

BATH BRUSH AND HOLDER.

Application filed January 23, 1924. Serial No. 688,011.

To all whom it may concern:

Be it known that I, NICHOLAS BURKART, a citizen of the United States, residing at Los Angeles, in the county of Los Angeles 5 and State of California, have invented a new and useful Bath Brush and Holder, of which the following is a specification.

This invention relates to bath room fixtures and more particularly to flesh brushes 10 designed to be supported on the bath tub.

The object of the invention is to provide a device of this character which may be removably mounted on a bath tub and used for scrubbing the back and for chiropractic 15 treatments.

Another object is to provide a brush holder having a stationary brush fixed thereto and a removable brush mounted thereon which may be replaced by a bath 20 towel when desired.

With the foregoing and other objects in view which will appear as the description proceeds, the invention resides in the combination and arrangement of parts and in 25 the details of construction hereinafter described and claimed, it being understood that changes in the precise embodiment of the invention hereindisclosed, may be made within the scope of what is claimed without 30 departing from the spirit of the invention.

In the accompanying drawings:—

Figure 1 represents a front elevation of a brush constructed in accordance with this invention.

Fig. 2 is a side elevation thereof; and Fig. 3 is a rear elevation.

In the embodiment illustrated the brush holder 1 is shown in the form of a plate of wood or other suitable material having a 40 brush 2 on its front face extending throughout a portion of its length and secured thereto in any suitable manner, the bristles of which are shown convex or curved longitudinally to conform to the curvature of 45 a person's back. This plate 1 is equipped with a spring clamp 6 designed to detachably secure a brush 5.

The clamp 6 which bears against one edge of the back of the brush 5 as shown clearly 50 in Fig. 2 is shown constructed of a coiled wire 7 mounted on a rod 8 carried by the upper end of plate 1 and which has a clamping jaw substantially L-shaped in end elevation which is designed to engage the edge 55 of the back of brush 5 and yieldably connect it to plate 1 by clamping it between the

upper edge of the back of brush 2 and said jaw.

The brush holder attaching device 10 comprises a piece of heavy wire bent intermediate its ends to form a loop 11 the members of which are connected by a clip 12 through which a screw 13 passes and enters the plate 1 to secure the member 10 thereto the loop 11 being arranged longitudinally relative to said plate.

The free ends of the wire diverge at the upper end of the plate as shown at 14 and then extend parallel for a portion of their length beyond the end of the brush to form 70 arms 15 which are curved rearwardly and provided at their terminals with inturned hooks 16 designed to engage the head or edge of a bath tub.

One end of the coil spring 7 is shown 75 engaged with one of the arms 14 to cause the spring to exert a clamping action on the jaw 6.

In the use of this brush holder the member 10 is mounted on a bath tub by hooking 80 the ends 16 over the edge of the tub and the brush 2 may then be used for scrubbing the bather's back it being understood that the bather rubs up and down on the brush. The brush 5 may be removed and used for 85 scrubbing other parts of the body and when through bathing a bath towel, not shown, may be held by the clamp 6 for drying the back or any suitable element may be substituted for the brush.

From the above description it will be obvious that a brush holder constructed as herein shown and described will be simple and cheap to manufacture and hence will be available for persons of all classes and it 95 may remain suspended from the bath tub when not in use or removed and stored in some convenient place.

I claim:—

1. A bath brush holder comprising a 100 plate having brush holding means on its front face and an attaching device secured to its rear face and made in the form of a heavy wire loop with a clip connecting the members of said loop, said members diverging at their free ends, said diverging ends extending beyond one end of said plate and being curved rearwardly and provided with inturned hooks to engage a support, the free ends of said hook being equipped 105 with thumb screws.

2. A bath brush holder comprising a

plate having a spring clamp carried by one end for engaging a brush to be held, and means on said plate to cooperate with said clamp, and an attaching device secured to the rear face of said plate and made in the form of a heavy wire loop with a clip connecting the members of said loop, said members diverging at their free ends and projecting beyond one end of said plate, said ends being curved rearwardly and pro-

vided with inturned hooks to engage a support.

In testimony that I claim the foregoing as my own, I have hereto affixed my signature in the presence of two witnesses.

NICHOLAS BURKART.
